INDICATING SQUARE

Edward H. Leszak, Amityville, N. Y.

Application February 21, 1944, Serial No. 523,297

3 Claims. (Cl. 33—112)

This invention relates to new and useful improvements in geometrical instruments and more particularly to a square, the principal object being to provide a square with an indicating instrument whereby the angularity of a surface being measured can be readily ascertained in degrees.

Other objects and advantages of the invention will become apparent to the reader of the following description.

In the drawings:

Figure 1 is an edge elevational view of one form of the invention.

Figure 2 is a side elevational view.

Figure 3 is a top plan view.

Figure 4 is a fragmentary top plan view of the short leg of the square.

Figure 5 is a vertical sectional view (fragmentary) through the form of the invention shown in Figure 1.

Figure 6 is a fragmentary vertical sectional view through a slightly modified form of the present invention.

Figure 7 is a fragmentary cross section on the line 7—7 of Figure 6.

Figure 8 is an edge elevational view of the third form of the invention with the lower portion in section.

Figure 9 is a side elevational view.

Figure 10 is a fragmentary vertical sectional view showing the gear means between the movable blade and the indicator.

Referring to the drawings wherein like numerals designate like parts, it can be seen that Figures 1 to 5, include the first form of the invention and this consists of an elongated leg 5 and a shorter leg 6, the latter being bifurcated as at 7 to receive the adjacent end of the longer leg 5, the legs being folded, doweled or otherwise secured together as at 8.

The long leg 5 is channeled throughout its entire length as at 9 to receive a blade 10 which is pivoted at its end opposed to the leg 6, within the channel 9 as at 11, while the opposite end has an arcuate slot 12 for receiving a cross pin 13 in the channel 9.

The free end of the leg 5 has a transverse bore 14 for receiving the shank 15 of an indicating instrument generally referred to by numeral 16, and a plunger 17 is slidable through this shank 17 for operating the indicating end of the indicator 16. This type of instrument is very conventional and a further description will be unnecessary. This type of instrument has a button 18 at the outer end of its plunger 17 and

in the present instance normally bears against a butt 19 on the opposed portion of the blade 10. A set screw 20 is feedable into the free end of the leg 5 to bite against the shank 15 of the instrument 16 to prevent displacement of the latter.

Obviously, when the leg 15 is placed against a structure with the blade 10 bearing against the surface thereof, the angular variance will be registered on the indicator 16.

10 A modification of the invention is shown in Figure 6 wherein a short leg 6a and a long leg 5a are fastened together as at 8a, the long leg 5a being channeled as at 9a to accommodate a blade 10a which has a pivot point as at 11a in opposed relation to the leg 6a and slightly inwardly of the pivot point 11a, the blade 10a is operative against the plunger 17a which operates into an indicating instrument 16a for operating the mechanism thereof. The indicating instrument 16a has a shank 15a apart from the plunger 17a and thus distinguish from the indicating instrument 16 and this shank may be secured to the leg 6a by suitable means. A spring-pressed button 21 is provided in the long leg 5a and acts against the blade 10a in the manner suggested in Figure 6.

15 The third form of the invention is shown in Figures 8 to 10, inclusive, and this consists of a short leg 6b fastened to a long leg 5b, the latter being provided with a transverse slot extending longitudinally thereof and in which a blade 10b is operative. The blade 10b is pivoted to the leg 5b adjacent the free end of the latter and as at 11b.

20 Where the leg 5b is fastened to the leg 6b, a threaded recess 23 is provided for receiving the threaded portion 24 of a screw 25 which is equipped with a tapered plug 26 engageable into a tapered opening 27 in the portion of the blade 10b opposed to the leg 6b. Obviously, by removing this plug 26 from the tapered recess 27, the blade 10b is free to operate in conjunction with an indicating instrument 16b. However, when the plug 26 is driven into the opening 27, the blade 10b is prevented from moving and the instrument serves as a rigid square.

25 The blade 10b adjacent the opening 27 has a transverse curved slot 28, along the upper edge of which is disposed a rack 29 which engages a gear 30 on a shaft 31, the shaft 31 extending into the indicating instrument 16b for operating the indicating hand or hands thereof. Numeral 32 denotes a spring friction element for the blade.

30 As can be seen in Figure 7, the release detent means 26 may be employed in conjunction with 55 the pin 11a in the form of the invention shown

in Figure 6, and in this connection the release detent is denoted by numeral 33.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In a device of the character described adapted to actuate an indicating instrument having an extending arm with a pinion thereon, a base member, an upright member positioned at an extremity of said base member in right angled relationship thereto to form a square, means forming a vertical slot in said upright member, a blade pivotally secured in said slot adjacent its upper extremity, said blade having an elongated slotted aperture adjacent the free end thereof, and a rack in said aperture engageable with said pinion.

2. In a device of the character described adapted to actuate an indicating instrument having an extending arm with a pinion thereon, a base member, an upright member positioned at an extremity of said base member in right angled relationship thereto to form a square, means

5 forming a vertical slot in said upright member, a blade pivotally secured in said slot adjacent its upper extremity, said blade having an elongated slotted aperture adjacent the free end thereof, a rack in said aperture engageable with said pinion, and a compression spring comprising a friction detent seated in a recess in said base member abutting said blade adapted to retain said rack and pinion in related assembly.

10 3. In a device of the character described adapted to actuate an indicating instrument having an extending arm with a pinion thereon, a base member, an upright member positioned at an extremity of said base member in right angled relationship thereto to form a square, means forming a vertical slot in said upright member, a blade pivotally secured in said slot adjacent its upper extremity, said blade having an elongated slotted aperture adjacent the free end thereof, a rack in said aperture engageable with 15 said pinion, a compression spring comprising a friction detent seated in a recess in said base member abutting said blade adapted to retain said rack and pinion in related assembly, and locking means comprising a detent on said base member engageable in a suitable aperture in the free end of said blade.

EDWARD H. LESZAK.
